223,717

SEAT FOR A HOBBY HORSE OR THE LIKE

Cid Garrison, 150 E. 69th St., New York, N.Y. 10021

Filed Nov. 24, 1970, Ser. No. 26,146

Term of patent 14 years

Int. Cl. D21—01

U.S. Cl. D34—15

FIG. 1

FIG. 2

FIG. 4

FIG. 3

FIG. 5

FIG. 6

FIG. 1 is a perspective view of a seat for a hobby horse or the like, showing my new design;
FIG. 2 is a top plan view thereof;
FIG. 3 is a side elevational view thereof;
FIG. 4 is a front elevational view thereof;
FIG. 5 is a rear elevational view thereof; and
FIG. 6 is a bottom plan view thereof.

I claim:

The ornamental design for a seat for a hobby horse or the like, as shown.
